UNITED STATES PATENT OFFICE.

CHARLES J. NASH, OF CHICAGO, ILLINOIS, ASSIGNEE TO THE WESTINGHOUSE AIR BRAKE COMPANY, OF PITTSBURGH, PENNSYLVANIA, A CORPORATION OF PENNSYLVANIA.

DRAFT-GEAR.

1,140,311.

Specification of Letters Patent. Patented May 18, 1915.

Application filed March 31, 1911. Serial No. 618,251.

To all whom it may concern:

Be it known that I, CHARLES J. NASH, a citizen of the United States, residing at Chicago, in the county of Cook and State of Illinois, have invented new and useful Improvements in Draft-Gear, of which the following is a specification.

My invention relates to draft gear for railway cars, and has for its principal object to provide an improved construction for mounting the draft gear on the car and for effecting the operation of same, of few parts and adapted to be cheaply manufactured.

In the accompanying drawing; Figure 1 is a central vertical section of a draft gear construction embodying my improvements; Fig. 2 a horizontal section thereof; Fig. 3 a transverse section thereof, on the line *a—a* of Fig. 2; Fig. 4 an isometric projection of the follower plate and a portion of the draft gear yoke; and Fig. 5 a horizontal section of a portion of the draft gear construction, showing the stops for the follower plate.

According to my invention, only one follower plate is required and vertical draft bolts or rivets are dispensed with. In lieu of the draft bolts a key plate is employed for transmitting the draw-bar stresses to the draft gear.

Instead of arranging the draft gear yoke vertically as usual, the same is located in a horizontal plane, so that the key plate may extend through the same for transmitting stresses to the draft gear without employing any additional plates or other parts.

As shown in the drawing, a draft gear yoke 1 is arranged horizontally between the car center sills 2 and mounted within said yoke is a draft gear 3 which may be of any desired construction, though the type shown is that known as the Westinghouse friction draft gear. The gear 3 is supported in the usual manner by a strap 4 secured to the under sides of the center sills 2 and the rearward end thereof is adapted to bear against the inner face of the yoke 1.

The forward ends of the yoke 1 are preferably thickened and are provided with horizontal rectangular slots 5 through which a key plate 6 is adapted to extend. The key plate 6 passes through a slot in the draw-bar 7 and is long enough to extend out beyond the center sills 2, which are provided with horizontal rectangular slots for that pur-

pose. The slots in the center sills are preferably reinforced by plates 8 having a flanged edge 9 adapted to fit into the sill slots. The plates 8 are secured to the center sills by means of rivets and are provided with ribs 10 between which the yoke 1 is mounted, as clearly shown in Fig. 1. The plates 8 are also provided with stops 11 against which the follower plate 12 is adapted to bear. The inner end of the draw-bar bears against the follower plate 12 and the rearward ends of the yoke 1 and the draft gear 3 are adapted to preferably engage the bolster center casting 13, although, if desired, a special casting may be secured between the center sills for that purpose.

The casting 13 is slotted to receive the yoke 1, so as to provide a rear support therefor. The follower plate 12 is provided with opposite horizontally arranged slots to permit the yoke 1 to extend through to the draw-bar, as shown in Fig. 4.

The draft gear 3, the yoke 1 and the follower plate 12 having been mounted in position between the car center sills, the draw-bar 7 is placed in position, and the key plate 6 is passed through the parts, said key plate being held in position by means of split pins 14 adjacent the bearing washers 15.

In operation, a buffing stress causes the draw-bar 7 to force the follower plate 12 rearwardly against the usual resisting force of the draft gear, the rearward end of the draft gear being held against movement by the casting 13.

The slots in the plates 8 are adapted to permit a certain rearward movement of the key-plate, 6 but just before the position is reached at which the draft gear would become "solid," the key plate is adapted to engage the end walls 9 of said slots and thus transmit further stress to the center sills, thereby preventing the extreme movement of the draft gear and the attendant effects of forcing draft gears "solid."

In draft, the draw-bar stress is transmitted from the key plate 6 to the yoke 1 and through said yoke the draft gear 3 is moved forwardly, the forward end of the draft gear being held from movement by means of the follower plate 12 engaging the stops 11. As in the case of buffing, before the "solid" position of the draft gear is reached, the key plate 6 engages the forward

flanged edges 9 of the plates 8, so that further stress is transmitted directly to the center sills.

It will now be evident that by means of my improvements, one follower plate and the stop lugs therefor are dispensed with, as well as the usual vertical bolts or rivets for securing the draw-bar to the yoke, and that a simple key plate arrangement is substituted for the vertical bolts without the necessity for employing any additional plates or parts. A simple construction adapted to be cheaply manufactured is thus provided.

Having now described my invention, what I claim as new and desire to secure by Letters Patent, is:

1. The combination with a yoke and a draft gear inclosed within the yoke, of a member mounted between the car center sills and provided with opposite longitudinal ledges and a transverse ledge forming a support for the rear end of the yoke.
2. In a draft gear and buffering apparatus for cars, the combination of a center sill composed of two parallel members, an abutment for the yoke located between and connecting said sill members, a yoke adapted to bear at its rear end against said abutment, a follower passing through the yoke, stops on the sill members in advance of the abutment for the rear end of the yoke for limiting the forward movement of said follower, shock absorbing means within the yoke and bearing at its front end against said follower and at its rear end against the rear end of the yoke, and a coupling connected with the yoke and having a limited movement independent of the latter, the said coupling adapted to bear against the fol-

lower and move same rearwardly under buffering stresses.

3. The combination of a center sill composed of parallel members, a combined stop and car body center bearing located between and secured to said members, a yoke adapted to bear against said combined stop and bearing in buffering and move away from same under pulling stresses, a coupler connected with the yoke and having a limited movement independent of the yoke, a follower passing through the yoke and adapted to be engaged by the rear end of the coupler, side stops for limiting the forward movement of said follower, and shock absorbing means within the yoke and bearing against the follower and rear end of the yoke.

4. The combination with a center sill, a member rigidly attached thereto and forming a part of them, a yoke adapted to bear at its rear end against the outer face of said member for transmitting buffering shocks to said sill, a coupler secured to said yoke and having a movement independent of the same, a front follower, stops located at the sides of the yoke and engaging the opposite ends of the follower for limiting the forward movement of said follower and shock absorbing means within the yoke and bearing at one end against the follower and at its other end against the rear end of the yoke.

In testimony whereof I have hereunto set my hand.

CHARLES J. NASH.
